UNITED STATES PATENT OFFICE.

HERMAN F. NEHR, OF NEW YORK, N. Y.

DESIGN FOR A ROSARY.

No. 37,875.

Specification for Design.

Patented March 6, 1906.

Application filed January 23, 1906. Serial No. 297,523. Term of patent 7 years.

To all whom it may concern:

Be it known that I, HERMAN F. NEHR, a citizen of the United States, and a resident of the city of New York, borough of Brooklyn, in the county of Kings and State of New York, have invented a new, original, and ornamental Design for a Rosary, reference being had to the accompanying drawing.

The figure is a plan view of a rosary, showing my new design.

I claim—

The ornamental design for a rosary as shown.

HERMAN F. NEHR.

Witnesses:

O. THOS. PHILLIPS,
PAUL BOETTIGHEIMER.
